(57) **CLAIM**

The ornamental design for a model vehicle axle carrier as shown and described.

DESCRIPTION

FIG. 1 is an upper, left, front perspective view, to include the mirror image, of a model vehicle axle carrier showing our new design;

FIG. 2 is an upper, right, rear perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is an upper plan view thereof;

FIG. 8 is a lower plan view thereof; and,

FIG. 9 is a lower, left, rear perspective view of a model vehicle axle carrier.

In the drawings, the broken lines illustrate portions of the model vehicle axle carrier that form no part of the claimed design.
